UNITED STATES PATENT OFFICE.

HERON L. CAUDLE, OF WADESBORO, NORTH CAROLINA.

GARMENT-SUPPORTER.

1,313,215.

Specification of Letters Patent.

Patented Aug. 12, 1919.

Application filed August 13, 1917. Serial No. 186,032.

To all whom it may concern:

Be it known that I, THERON L. CAUDLE, a citizen of the United States, and a resident of Wadesboro, in the county of Anson and State of North Carolina, have invented a new and useful Improvement in Garment-Supporters, of which the following is a specification.

My invention relates to improvements in garment supporters, it being designed more particularly for use in supporting trousers, and it consists of the constructions, combinations, and arrangements herein described and claimed.

15 An object of my invention is to provide a device for supporting trousers, by the use of which, suspenders may be dispensed with entirely, and a belt may be worn for appearances only.

20 Another object of the invention is to provide a device for supporting trousers, which comprises a flexible or pliant body having wings insertible between the facing band and cloth of the trousers at the waistline, 25 and a pendent member having a loop which is adapted to be hooked over a hook detachably supported on the shirt of the wearer, the loop in turn, having a resilient support so that the wearer of the device may obtain 30 all freedom of movement.

Another object of the invention is to make one of the wing members separable from the body of the device so that the device may be more easily applied to the trousers, and the 35 adjustment of the device facilitated.

Other objects and advantages will appear in the following specification, reference being had to the accompanying drawings in which:

40 Figure 1 is a perspective view showing the garment supporter applied to the trousers.

Fig. 2 is a perspective view showing how the loop of the garment supporter hooks over 45 the hook carried by the shirt of the wearer.

Fig. 3 is a side elevation of the device, a portion of the trousers being broken away.

Fig. 4 is a cross section on the line 4—4 of Fig. 3.

50 Fig. 5 is a side elevation of the garment supporter viewed from the inside.

Fig. 6 is a cross section on the line 6—6 of Fig. 5, and

Fig. 7 is a perspective view showing a

modification of the garment supporter where- 55 in the body is made of leather or other similar pliant material.

Reference is directed to Figs. 1 and 2 of the drawing, wherein it will be seen, the garment supporter 1 is fixed upon or carried by 60 the trousers 2. The garment supporter 1 includes oppositely extending wing-like members 3 and 4 which are adapted to be located in a pocket 5 formed between the cloth of the trousers 2 and the facing band 6 of the 65 trousers.

The trousers supporter 1 is applied by cutting a slit 7 in the facing band 6, thus forming an opening through which the wings 3 and 4 may be inserted sidewise. Ordinarily 70 no means other than of simply the frictional engagement of the wings of the supporter 1 against the cloth sides of the pocket 5, need be provided to hold the supporter in place, but it is preferable to provide some suitable 75 fastening means, as a button 14^a as shown in Fig. 4. Or similar buttons may be arranged at a plurality of places on the lower edges of the wings 3 and 4. The buttons thus perform the added function of holding the fac- 80 ing band down. Obviously, however, the wings may be suitably perforated at places to permit the insertion of "bachelor buttons" to hold the supporter in place on the trousers, if it be so desired. 85

A hook 8 is fixed on the shirt 9 of the wearer, by fitting the loop of the hook 8 over the neck of a button 10 which is inserted from the inside of the shirt substantially as shown in Fig. 4. The cloth of the shirt 9 is, 90 of course, drawn around the neck of the button 10, when the loop of the hook 8 is pulled thereover. The hook 8 is adapted to remain in position on the shirt during the period of use thereof. 95

A rectangular loop member 11 is carried by the garment supporter 1 and is adapted to be hooked over the hook 8. The loop 11 is in turn carried by an elastic band 12 and is disposed on the inside of the garment 100 supporter, so that the loop 11 may be fitted over the hook to support the trousers as indicated in Fig. 2.

The ends of the elastic band 12 are threaded through slots 13 in the pendent member 14 of the supporter 1. An adjusting buckle 15 serves to tighten the elastic band 12 when it becomes necessary to do so. The pendent

member 14 is joined with the wing 4 through a neck 16. It will be seen that the pendent member 14 and the wing 4 are made of one piece in the preferred form of the invention.

5 The wing 3 is detachable and is provided with a pair of hooks 17 arranged to be fitted in openings 18 in the wing 4 when the parts are assembled as shown in Fig. 3.

It will be observed in Fig. 6, that the 10 hooks 17 include right-angled portions which terminate in bent ends 17^a. The ends 17^a come on the outside of the device next to the cloth of the trousers, and the surfaces of the wings 3 and 4 are practically 15 continuous on the inside next to the body of the wearer. The joint between the wings 3 and 4 just described, permits the separation of the wing 3 from the body of the supporter, and affords an easier introduction of 20 the device into the pocket 5.

In the preferred form of the invention, the garment supporter is made of some resilient rust-proof metal, and covered with cloth 19 as indicated in the drawing. The 25 resilient nature of the metal of which the device is adapted to be made, permits the pendant 14 to flex at the neck 16, while the wings 3 and 4 may flex equally as well throughout their lengths, and independently 30 of the hinge joint at 18.

The modified form of the invention illustrated in Fig. 7, is essentially the same as the form illustrated in the other figures. Here, however, the garment supporter 1, 35 consists of a body made of leather or any other similar pliable material. The pendant 14 is made integral with the wings 3 and 4. In applying this form of the invention, it may be found desirable to use some 40 such fastening means as a "bachelor button" which includes the shank 20 and head 21. The garment supporter 1 shown in Fig. 7 is fitted in the pocket 5 provided between the facing 6 and cloth of the trousers 2, in the 45 same manner as the garment supporter of the other form is fitted in place. The shank 20 of the "bachelor button" is then thrust through the cloth of the trousers 2, and the head 21 pushed in place to hold the pendant 14 down.

50 The operation of the garment supporter is as follows: One of the garment supporters 1 is fitted in the pocket 5 between the facing band and cloth of the trousers 2, at each side of the trousers and preferably right on the seams of the trousers. In Fig. 1, only one of the trousers supporters 1 is shown, it being understood, however, that there is another on the other side. The 55 button 10 and hook 8 are fitted in place on the shirt 9 on each side of the shirt and preferably on the seams which join the back and front of the shirt. The pendant 14 hangs down as shown in Fig. 2, and when it is 60 desired to support the trousers by the shirt,

the loop member 11 is hooked over the hook 8 and the trousers are thus supported. The elastic band 12 forms a resilient connection between the shirt and the trousers, and perfect freedom of the movement of the arms 70 of the wearer is had, because the elastic bands 12 of each supporter will properly give.

It will also be observed that the connections between the shirt and the trousers, consisting of the button 10, hook 8, and loop 11, are entirely concealed from view. The application of the hook 8 right on the 75 seam of the shirt 9 at each side, prevents the shirt from becoming easily torn or worn because the seam acts as a reinforcing 80 member.

It will readily be understood from the foregoing, that in order to apply the wings 3 and 4, the facing band 6 must be slit substantially as indicated in Fig. 1, to permit 85 the introduction thereof into the pocket 5. The wings 3 and 4 are then thrust in the opening thus provided, and to do this, the wings must be separated. In order to separate the wings, the wing member 3 is rotated 90 in an outward direction a sufficient distance to permit the disengagement of the shank 17 and bent ends 17^a from the openings 18.

While the construction of the device as 95 illustrated in the drawings is that of a generally preferred form, obviously modifications and changes may be made therein without departing from the spirit of the invention or the scope of the claims.

I claim:

1. In a garment supporter, a resilient body having outstanding wings, adapted to be secured on a garment, an elastic band looped through portions of the said body and having means for adjusting the same, and an engaging loop through which the said band is also extended.

2. In a garment supporter, a flexible supporting body including wings adapted to be located in a pocket formed between the facing band and cloth of the trousers, said body including a pendent member, an elastic band mounted on the pendent member and having an adjusting buckle on the outside, and a loop carried by the elastic band on the inside of the supporting body.

3. In a garment supporter, a supporting body including separable wing members adapted to be located in a pocket formed between the facing band and cloth of a garment, and a pendent carried by one of the wing members, the pendent having slots, an elastic band having the ends threaded through the slots and provided with an adjusting buckle on the outside, and a loop carried by the elastic band on the inside of the supporting body.

4. In a garment supporter, including a flexible supporting body having a wing and a pair of openings, a detachable wing hav-

ing hook members with bent ends adapted to enter the openings and lie on the inner surface of the garment supporter, to preserve the continuity of the flexible body.

5. In a supporter, the combination of a garment having a facing band forming a pocket, said band being adapted to be slitted, a supporting body including lateral wings adapted to be located in the pocket, one of 10 said wings being separable from the body to permit introduction of the wings through the slit into the pocket, and means arranged on the separable wing and the supporting body for detachably securing them together.
- 15 6. In a supporter, the combination of a garment having a pocket, and a supporting body having wings adapted to be located in the pocket to hold the supporter on the garment, said supporting body being adapted

to be held in place by frictional contact and 20 without the use of thread.

7. In a device of the character described, a supporting member having means for engagement with the waist-band of the lower garment and projecting downward therefrom, a separate fastening device for engagement with the upper garment in the region of the waist line, and a resilient connection between said fastening device and the lower portion of said supporting member, said resilient connection normally holding the garments in adjusted co-operative relation and being yieldable in every direction to compensate for the movements of the body and permit corresponding relative movement of the garments. 25 30 35

THERON L. CAUDLE.
